C. P. CROSSMAN.

Tempering Scythes.

No. 17,872.

Patented July 28, 1857.

Fig. 2.

UNITED STATES PATENT OFFICE.

C. P. CROSSMAN, OF WARREN, MASSACHUSETTS.

MACHINE FOR TEMPERING SCYTHES.

Specification of Letters Patent No. 17,872, dated July 28, 1857.

To all whom it may concern:

Be it known that I, C. P. CROSSMAN, of Warren, in the county of Worcester and State of Massachusetts, have invented a new 5 and Improved Implement or Device for Tempering Scythes and Similar Tools or Implements; and I do hereby declare that the following is a full, clear, and exact description of the same, reference being had to 10 the annexed drawings, making a part of this specification, in which—

Figure 1, is a longitudinal vertical section of my improvement; (x), (x), Fig. 2 indicating the plane of section. Fig. 2, is a 15 transverse vertical section of ditto; (y), (y), Fig. 1 indicating the plane of section.

Similar letters of reference indicate corresponding parts in the two figures.

This invention consists in the employment 20 within a suitable water tank of a pair of movable jaws and boxes, for seizing, holding, and conveying the scythe-blade or other article while being tempered, substantially as hereinafter described.

25 To enable those skilled in the art to make and use my invention, I will proceed to describe its construction and operation.

A represents a rectangular box or tank which forms a water reservoir. This box or 30 tank is constructed of wood, and should be rather longer than the tool to be tempered. Within the tank or box A two pairs of guides (a), (a), (b), (b), are placed. The lower parts of these guides are in a vertical 35 position within the box or tank; but their upper parts are curved toward the sides of the box or tank, as shown clearly in Fig. 2.

B represents a treadle, one end of which is fitted and works loosely in a socket (c), attached to the base C of the box or tank.

D, D, represent two jaws. These jaws are formed of iron bars, curved so as to correspond in form to the tool they are intended to grasp; the tool in the present instance 45 being a scythe, such tool being represented in the drawings and designated by E. The jaws D are transversely of triangular or an approximating form, and their face or sides which grasp the tool are quite narrow, see 50 Fig. 2. The jaws D are attached to the upper ends of two pairs of cross levers F, F, the lower ends of which have plates (d) attached to them, one to each; said plates working between the guides (a), (a), (b), (b). Each 55 pair of levers works on a fulcrum pin (e), and the plates (d), of each pair of levers have

the ends of a semi-circular spring (f), attached to them as shown clearly in Fig. 2. The springs (f) have a tendency to keep the jaws distended. Short arms or bars (g) are 60 also attached to the jaws D, the lower ends of which arms are pivoted in boxes (h).

The two pairs of arms (g) nearest the central portion of the arms are connected at their lower ends by a cross bar (i), and this 65 bar (i) has a curved rod (j) attached to it; said rod being connected to the treadle B.

The operation is as follows:—The box or tank A is supplied with the requisite quantity of water, and the scythe E being properly heated is placed by the operator between the jaws D D the back of the scythe resting on the boxes (h). The operator then places his foot on the treadle B and depresses it, and as the plates (d) of the levers 70 F F pass between the parallel and vertical portions of the guides (a), (a), (b), (b), the lower and also the upper ends of said levers will be forced toward each other and the jaws D D will firmly grasp the scythe E, 75 which, when the treadle is fully depressed, will be immersed in the water and tempered or hardened, the jaws D preventing the scythe from warping or springing in consequence of being thus immersed in the water 80 while in a heated state. When the scythe has been immersed a sufficient length of time the operator allows the treadle to rise, and the jaws D, when the plates (d) at their lower ends of the levers F reach the rounded 85 upper ends of the guides (a), (a), (b), (b), are expanded or distended by the springs (f), and the operator withdraws the tempered scythe from between the jaws and places 90 another there to be operated on as before. 95

Scythes, knives, and similar tools, are always warped or sprung in a greater or less degree in the tempering, and considerable time is expended in bringing them to their original and proper shape. This labor augments, of course, the price of the tool; besides, the proper temper is often impaired and the tools frequently broken in endeavoring to remedy the difficulty. By my improvement this difficulty is avoided by a 100 very simple mechanism, and one that may be constructed at a small cost.

I do not claim, broadly, clamping tools or other articles, or securing them between jaws so that said articles cannot warp or 105 spring while being immersed in water in a heated state, for the purpose of tempering or

hardening them, for cast iron plates for grinding mills and other articles have been thus treated for the same purpose.

In the patents granted to A. Wheeler, 5 1849, and J. N. Rockwell, 1857, the ax to be tempered is placed within a box, into which water is admitted after the ax has been lowered into the bottom of the box. In the rejected application of Moss and Earle, 10 1852, a steel sheet is held while being tempered between two plates that are provided with projecting pins.

I do not claim either of the above devices. In neither of them is there employed a pair 15 of movable jaws and boxes, so arranged that, when the article to be tempered is placed upon the boxes, and pressure applied to a pedal, the jaws will seize hold and convey the article into the water.

20 In the use of my improvement it will be

observed that the cutting edge of the scythe projects above the jaws D, when the latter are closed. The water is thus allowed to have free access to the cutting edge of the scythe, and the tempering is rendered uniform throughout; at the same time, as before stated, the scythe is firmly held between the jaws, and entirely prevented from warping.

What I claim as new, and desire to secure 30 by Letters Patent, is:

The employment within a suitable water tank A, of a pair of movable jaws D, and boxes (h), for the purpose of seizing, holding, and conveying the scythe blade, all substantially as described.

C. P. CROSSMAN.
